SMOKING PIPE

Stanley Brown, Garden City, N. Y.

Application November 21, 1931, Serial No. 576,480

19 Claims. (Cl. 131—12)

My invention relates to improvements in tobacco pipes, and particularly tobacco pipes the bowl and the stem of which are detachably connected.

5 An object of the invention is to provide a tobacco pipe having a stem which will be firmly engaged and yet easily separable from the bowl thereof; even when the parts are in moist or soggy and expanded condition; to enable the pipe to be 10 cleaned and for other purposes.

A pipe of this character will meet the needs of smokers who find it very difficult to take ordinary pipes apart. For instance, a pipe which has a stem suitably fitting the bowl while being 15 smoked, will, if laid aside for a time to dry, soon attain a state in which the stem sticks fast to the bowl and cannot be removed until the pipe is again smoked and allowed to moisten. When dry, the stem and bowl adhere together very 20 firmly, but when moist, the stem can be taken out. The moistening of the parts may result in a small increase in the diameter of the hole in the bowl to receive the stem. This increase, as 25 the stem and bowl no longer stick fast, facilitates the separation thereof.

Another object of the invention is to provide a tobacco pipe of such construction that one of the chief members thereof, such as the stem or the bowl, will be held in place by a clamping effect 30 sufficient to join the principal parts of the pipe securely together, while at the same time the stem can be readily withdrawn from the bowl when the smoker desires. In one case the stem of the pipe may be adapted to give somewhat, and 35 in another form the bowl may be designed to have such an action; or if preferred, both the bowl and the stem can be made to cooperate in this way. In other embodiments, an additional element may be provided to engage the bowl on the one hand 40 and the stem on the other in a manner to maintain the firm engagement of these parts, but always in condition to enable the pipe and stem to be disconnected.

A further object of the invention is to provide 45 a tobacco pipe of such construction that the opening to receive the stem is of large size, and the communication from this hole to the tobacco chamber is likewise of large size, so as to facilitate cleaning and airing when the pipe is 50 disassembled. With the variation of the wood between dry and soggy condition, the moderate change in dimensions requires extra care for the sealing between stem and bowl. To this end, resilient means are provided to hold the stem 55 and the bowl in continuously sealed relation.

An additional object is to impart to a bowl having large openings and passages a resilience which holds the stem in the opening at the bottom of the tobacco chamber in sealed relation, in spite of the variation of the wood. 60

With these and other objects and advantages in view, as will appear from the ensuing description, taken with the accompanying drawings; the invention comprises the various embodiments herein disclosed, and the essential novel features 65 are pointed out in the appended claims.

On the drawings:

Fig. 1 is a side view partly in section of one form of pipe according to this invention;

Fig. 1a is a cross section of Fig. 1, taken on 70 line a—a;

Figs. 2 and 3 are sectional views of the separated bowl and one end of the stem, respectively, of such a pipe;

Fig. 4 is a bottom plan thereof;

Fig. 5 is an end view and Fig. 6 is a longitudinal sectional view of another form of pipe according to this invention;

Fig. 7 is a sectional view of the bowl thereof;

Fig. 8 is a top plan of the stem thereof;

Fig. 9 is a front view and Fig. 10 is a bottom view of another modification of my invention;

Fig. 11 is a top view of an additional element for obtaining firm but yieldable connection between the stem and bowl of said modification;

Fig. 12 is a sectional view of a bowl and part of a stem of a further embodiment;

Fig. 13 is a bottom view thereof;

Fig. 14 is a side view of an element for affording firm but yieldable engagement between the 90 stem and bowl of said embodiment;

Figs. 15 and 16 show details of the last-named modification;

Fig. 17 shows a longitudinal section of a pipe according to an additional modification of the 95 invention;

Fig. 18 is a top plan of the detached stem thereof; and

Fig. 19 is a bottom plan of the bowl of the pipe appearing in Fig. 17.

On the drawings the same numerals identify the same parts throughout.

Referring first to Figs. 1, 2, 3 and 4, I show a pipe comprising a bowl 1 with a detachable stem 2. The bowl 1 has a chamber or cavity 3 for the 105 tobacco and an opening 4 in the bottom. The bowl also has a transverse passage or bore 5 adjacent the bottom communicating with both the opening 4 and chamber 3; and the end of the stem 2 fits into this bore when the bowl is mounted 110

on the stem 2. To make the bowl 1 and stem 2 fit together firmly but yieldably, a longitudinal cut or slit 6 is made in the end of the stem 2. Hence the stem can be made with its outside diameter at least as large as the inside diameter of the hole 5; and upon the end of the stem being forced into the opening 5, the portions separated by the cut 6 will be forced toward each other but will be sufficiently resilient to press outwardly 10 against the inside walls or surfaces of this passage and bring about a tight fit between the bowl and stem. On the lower side of the stem, I form a bevelled projection 7, one end of which terminates in an abrupt shoulder 8 to engage the edge of the opening 4 and thus prevent withdrawal of the stem; but when pressure is exerted against this bevelled projection to force up the part of the stem at one side of the cut 6 far enough to enable the shoulder 8 to clear the opening 4, the projection 20 permits the stem to be withdrawn. The stem also has on its outside a shoulder 9 opposing the shoulder 8 to engage the exterior of the bowl adjacent the bottom and prevent the stem from being forced too far into the bowl. On the top side 25 of the stem at the inner end there may be a recess 10 which forms the bottom of the chamber 3 when the stem is in place; and the stem has a longitudinal air flue or passage 11 extending from the outer end of the stem through the entire length 30 thereof, and communicating with the recess 10.

With this form of pipe, the stem can be slipped into place merely by putting one end into the opening of the passage 5 and pushing the stem till the bevelled latch projection 7 reaches the opening 4 and spans same with the shoulder 8 engaging the edge of this opening at one point. During insertion, the two parts of the stem on both sides of the cut 6 will yield to sufficient extent for the latch projection 7 to enter the bore 40 5; and upon reaching the opening 4, the end of the stem will expand so that this projection springs outward into the opening 4. The bowl is then securely mounted on the stem so that it cannot be taken off, unless the latch 7 is first released from the bottom opening 4. The sides of 45 this projection are curved as shown in Figs. 1a so that, by the turning of the stem, the edge of the hole 4 bears with increasing pressure as the slope of the curved protuberance or projection 7 increases, and the latching shoulder 8 is pushed 50 inwardly and out of engagement. Then as soon as the shoulder 8 clears the edge of the opening 4 the stem 2 can be pulled out.

In the form shown in Figs. 5 to 8 inclusive, the bore 5 is placed lower down as shown at 5a so that this bore opens on one side through the bottom of the bowl 1. The stem 2' tapers somewhat over the portion which is to lie within the bore 5a and this portion may be flattened at its 60 lower side as shown at 12. The cut 6 makes the stem 2' yieldable as before and the bowl 1 may be yieldable to a slight extent, because of the presence of the bore 5a which bisects the bottom thereof. The pipe and the stem thus cooperate and a double clamping effect is thus produced. Whenever the stem 2' is to be removed it is actuated in such a direction that the stem passes along the bore 5a, the end with the cut 6 leading in the course of this movement.

70 In the form shown in Figs. 9, 10 and 11, the bowl has a bore 5b which is open at one side through the bottom of the bowl and has straight instead of curved sides 13. A resilient element 75 in the form of a split tubular sleeve 14 is provided to grip the end of the stem and to be seated

in the bore or recess 5b. This split sleeve has an aperture 16 in the top which communicates with the chamber 3 in the bowl and along the bottom it has separated edges 15 formed to provide a large central space 16a. At the sides of the element 14 are projections 18 to enter recesses in the sides of the bore 5b. This element can be put in place separately forcing it into the bore 5b until the projections 18 register with the recesses and then the sides of the sleeve spring apart so that the sleeve remains in place. The fit between the element 14 and the sides 13 of the bore 5b will not be snug so that when the end of the stem 2, which is cylindrical, is inserted, the sides of the elements 14 can yield a bit and grip the stem 2 firmly. For this purpose the outside diameter of the end of the stem 2 can be slightly larger than the inside diameter of the sleeve 14 when the latter is in place in the bowl, and the stem 2 need not have a split end. The element 14 will then clamp the stem and hold it as firmly as necessary.

In Figs. 12 to 16 inclusive the bowl 1 is made with a bore 5c which is like that shown at 5b, but does not pass through the bowl 1 from side to side. The connecting element for the bowl and stem has the form of a split cylindrical sleeve 14c with separated edges 15 shaped to provide an enlarged central place 16a in its bottom and with a boss 18 projecting from the upper side 105 thereof. This element is inserted into the bore or recess 5c and the boss 18 projects into the bottom of chamber 3 and is afterwards expanded as shown at 18a, to keep it from being pulled out. The cylindrical end of the stem is forced into this 110 clamping sleeve 14a and is firmly but yieldably held thereby as before. The stem at its inner end has a recess 10a which registers with the boss 18.

Figs. 17, 18 and 19 show a pipe with an elongated opening 4a in the bottom and with the stem 2 counterbored to provide an enlarged passage in line with the air flue 11 to receive a short length of tubing 19 split longitudinally over a part of its length as shown at 20. The bowl 1 has a neck 120 21 through which leads a bore into which tubing 19 can be inserted. The bore in question stops short of the other side of the bowl so that the tubing 19 extends across the opening 4a and the slit 20 establishes communication between the 125 air passage 11 in the stem and the chamber 3. The end of the stem 2 is bevelled as shown at 22 to fit within the corresponding shaped end of the neck 21. The piece of tubing 19 will be attached to the stem 2 and it will have a tight fit with the 130 bowl 1, being compressed when it is forced into the bowl and expanding a little when it is pulled out. This construction also facilitates the easy connection of the bowl and stem and the ready separation of these two parts.

In this last modification the attachable relation of the bowl and stem and the relatively large extent of the bottom hole 4a have a decided cooling effect by reason of the exposure of the lower side of the sleeve 19 through the bottom of the 140 bowl to the air. This effect is also obtained in some degree by the other forms of my improved pipe in all of which the lower sides of the terminal portions of the stems adjacent the bowls are similarly exposed.

In my invention as above described the separable bowl and stem facilitate cleaning the pipe and the resilient engagement of the bowl and stem seals the bottom of the tobacco chamber and the upper side of the end of the stem within said 145 150

chamber. This resilient engagement is further necessary to make the bowl shankless and to make the openings at the bottom relatively large in area.

5. A pipe construction as above described is very strong because in all the forms shown the joint between the stem and bowl is quite durable. If desired the hole 4a in the pipe of Fig. 17 may be omitted, and the split sleeve 19 may terminate 10 in neck 21, which may then be longer.

From the foregoing construction it will be seen that the objects of my invention are fully obtained and while I have shown certain specific embodiments thereof, I do not wish to be 15 limited to the exact details set forth, but reserve the right to make changes which do not depart from the essential principle of the invention.

Having described my invention, what I believe to be new and desire to protect by United States 20 Letters Patent is:

1. A tobacco pipe in separate parts comprising a bowl and a detachable stem, the bowl having a transversely extending opening to receive one end of the stem, one of said parts having means 25 constructed and adapted to cause said end of the stem to be firmly but yieldably clamped within said opening to connect it with the bowl, to hold said parts together, and at the same time permit removal of the stem, the bowl also having 30 an opening in the bottom closed by said stem when the latter is operatively connected to said bowl.

2. A tobacco pipe comprising a bowl and a stem, the bowl having a transversely extending opening to receive one end of the stem, the bowl having 35 means within said opening to clamp said end of the stem in firm but yielding engagement therewith, and at the same time to permit the easy removal of the stem.

3. A tobacco pipe comprising a bowl and a detachable stem, the bowl having a transversely extending opening to receive one end of the stem, said bowl and said stem having means constructed and adapted to cause said end of the stem to be 45 clamped within said opening in yieldable engagement with the bowl, to secure said parts firmly together, and permit the easy disconnection of one from the other, the bowl also having an opening in the bottom closed by said stem when the latter is operatively connected to said bowl.

50 4. A tobacco pipe having a bowl containing a cavity and an opening in the bottom, said bowl also having an opening extending into the same at one side and communicating with both the cavity and the first opening, and a stem having a split end to be inserted into said opening and make a resilient fit with the bowl, to hold the bowl and stem together, and to permit the ready separation thereof.

5. A tobacco pipe comprising a bowl having a cavity therein, a hole extending into the bowl from one side, said hole communicating with the cavity and opening through the bottom of the bowl, and a stem having a split end to be disposed within the hole and fit the same resiliently, 65 to hold the parts together, and at the same time permit the removal of the stem.

6. A tobacco pipe comprising a bowl having a cavity therein, an opening extending into the bowl from one side, said opening communicating 70 with the cavity and being open along its length through the bottom of the bowl, and a stem having a split end to be disposed within the opening and fit the same resiliently, to hold the parts together, and at the same time permit the removal 75 of the stem, both the opening and the split end

of the stem being tapered to make secure connection between the bowl and the stem.

7. A tobacco pipe comprising a bowl and a detachable stem, the bowl having a chamber therein and a hole extending into the bowl from one side communicating with said chamber and opening through the bottom of the bowl, and a split clamping sleeve in said hole to receive the end of the stem, to hold the bowl and stem in secure connection, and permit the separation of said parts. 80

8. A tobacco pipe having a bowl with a cavity therein and a detachable stem, the bowl having a hole extending into one side, the hole having an opening along its length through the bottom of the bowl and communicating with said cavity, a split clamping sleeve in said bore open on its lower side through the bottom of the bowl, said sleeve having a neck or boss at its opposite side expanded into engagement with the lower end of the cavity to retain said sleeve in place, the stem being inserted into said sleeve and having a smoke communicating hole in registry with said expanded boss, the stem being firmly but yieldably secured to the bowl by said sleeve. 85

9. A tobacco pipe having a bowl with a cavity therein and a detachable stem, the bowl having a hole extending into one side, the hole having an opening along its length through the bottom of the bowl and communicating with said cavity, a split clamping sleeve in said hole open on its lower side through the bottom of the bowl, said sleeve having a neck or boss at its opposite side expanded into engagement with the lower end of the cavity to retain said sleeve in place, the stem being inserted into said sleeve and having a recess to register with said expanded boss, the stem being firmly but yieldably secured to the bowl by said sleeve. 100

10. A tobacco pipe having a bowl containing a cavity and an opening in the bottom thereof, said bowl also having a hole extending laterally through the wall and communicating at one side with said cavity and at the opposite side with the opening, and a stem having a length of split tubing at its inner end to be inserted into said bore with the split side presented to the cavity in the bowl, the tubing making a tight fit with the inside of the hole to hold the bowl and stem tightly but releasably together. 115

11. A tobacco pipe having a bowl containing a cavity and an opening in the bottom thereof, said bowl also having a hole extending laterally through the wall and communicating at one side with said cavity and at the opposite side with the opening, and a stem having a length of split tubing at its inner end to be inserted into said hole with the split side presented to the cavity in the bowl, the tubing making a tight fit with the inside of the hole to hold the bowl and stem tightly but releasably together, the outer end of said hole being counterbored and the adjacent portion of the stem having a conical shoulder to engage said counterbored hole. 130

12. A smoking pipe comprising a bowl having a tobacco cavity therein, and a transverse opening extending into the bowl and communicating with the tobacco cavity, and a removable stem one end of which is recessed within said transverse opening, the pipe also having resilient means acting in said opening to secure said end of the stem in sealed relation against the inside of the communicating passage to the tobacco cavity. 140

13. A smoking pipe comprising a bowl and a removable stem, the bowl having a cavity to re- 145

ceive tobacco, and having in communication with the cavity a hole to receive the stem, and having resilient means acting in said hole to cause the end of the stem to be yieldably gripped therein to maintain the sealed connection of the stem and bowl, said bowl also having an opening in the bottom which is closed by the stem.

14. A smoking pipe comprising a bowl and a removable stem, the bowl having a chamber and a lateral opening leading to the chamber, one end of the stem being fitted into the opening, the bottom of the bowl having another opening to expose the lateral surface of the stem adjacent the inner end thereof through the bottom to the atmosphere, the stem sealing the second opening, the pipe having resilient means in said latter opening for causing said stem to be gripped therein to maintain the bowl and stem in sealed relation.

15. A tobacco pipe comprising a bowl and a stem, the bowl having a transverse opening to receive one end of the stem, the bowl having means in said opening acting to clamp said end of the stem in firm but yielding engagement therewith to permit the removal of the stem, the bottom of said bowl also having an opening which is sealed by said stem.

16. A tobacco pipe comprising a bowl, and a detachable stem, the bowl having a transverse opening to receive the one end of the stem, the latter having means acting within said opening to enable said end of the stem to be yieldably and releasably clamped therein but to hold the stem and bowl together while permitting easy separation thereof; the bowl also having an opening

through the bottom to be sealed by the end of the stem.

17. A tobacco pipe comprising a bowl and a detachable stem, the bowl having a transverse opening to receive one end of the stem, said bowl and said stem being constructed to provide means to enable said end of the stem to be yieldably clamped within the opening to secure the stem in place but permitting the easy removal thereof, the said bowl also having an opening at the bottom which is sealed by the stem.

18. A smoking pipe comprising a bowl and a removable stem, said bowl having a tobacco cavity and an opening in its side communicating with the cavity along the bottom thereof, said opening being adapted to receive the stem, the latter having its inner end in the form of an expansible tube which, when the bowl and stem are assembled, seals and forms the bottom of the cavity, and forms the sole means for removably securing the stem in place in the bowl.

19. A smoking pipe comprising a bowl and removable stem, said bowl having a tobacco cavity with an opening through the bottom of the bowl, said bowl also having a hole in its side, communicating with the cavity along the lower part thereof, said hole being adapted to receive the stem, the latter having its inner end in the form of an expansible tube which, when the stem is in position with respect to the bowl, forms the bottom of the cavity and seals said cavity from the opening in the bottom.
